UNITED STATES PATENT OFFICE.

JOSEPH A. CRAIG, OF ROSCOE, PENNSYLVANIA.

MINE-CAR RAIL.

SPECIFICATION forming part of Letters Patent No. 707,999, dated August 26, 1902.

Application filed October 16, 1901. Serial No. 78,779. (No model.)

To all whom it may concern:

Be it known that I, JOSEPH A. CRAIG, a citizen of the United States, residing at Roscoe, in the county of Washington and State of Pennsylvania, have invented a new and useful Improvement in Mine-Car Rails, of which improvement the following is a specification.

This invention relates to certain new and useful improvements in rail-joints, and relates more particularly to that class wherein the use of fish-plates is entirely dispensed with.

The invention consists in the novel combination and arrangement of parts to be hereininafter more fully described, and specifically pointed out in the claim.

In describing the invention in detail reference is had to the accompanying drawings, forming a part of this specification, and wherein like numerals of reference indicate corresponding parts throughout the several views, in which—

Figure 1 is an end view of the rail having my improved rail-joints attached thereto. Fig. 2 is a top plan view thereof. Fig. 3 is a perspective view of the inner clamp. Fig. 4 is a perspective view of the outer clamp.

In the drawings the reference-numeral 1 indicates the rail, and 2 represents the metallic tie, having openings 3 formed therein for the reception of bolts or other fastening means.

The reference-numeral 4 represents an inner clamp, having an inclined portion 5 formed integral therewith to engage the base of the rail, said inner clamp having also formed therein an opening 6, through which extends a bolt 7, which is secured in position by means of the nut 8, engaging the screw-threaded portion of the bolt.

The reference-numeral 9 indicates the outer clamp, having a slot 10 formed therein and carrying an integral fish-plate 11, forming a portion of the chair.

The reference-numeral 12 indicates a bolt 45 secured to one of the openings 3, extending through the slot 10 and held in position by means of a nut 14.

The manner of operating my improved rail-joint will be readily understood by referring 50 to Fig. 2 of the drawings, where the movement of the inner clamp is shown and illustrated in dotted lines.

It will be noted that numerous advantages are obtained by the herein-described construction, which will allow for the expansion and contraction of the rails caused by the differences in temperature.

It will be noted that various changes may be made in the details of construction without departing from the general spirit of my invention.

Having fully described my invention, what I claim as new, and desire to secure by Letters Patent, is—

A rail-joint comprising in combination with a chair 9 having a transverse slot 10 and an upwardly-projecting portion adapted to be held against the under face of the tread of the rail, a swinging plate 4 and retaining pivotal bolt, the free end of said plate 4 being rounded and adapted to wedge against the web of a rail as set forth.

In testimony whereof I have hereunto signed my name in the presence of two subscribing witnesses.

JOSEPH A. CRAIG.
